LEROY C. DOANE, OF MERIDEN, CONNECTICUT, ASSIGNOR TO THE MILLER COMPANY, OF MERIDEN, CONNECTICUT, A CORPORATION OF CONNECTICUT

LIGHTING FIXTURE

Application filed March 9, 1927. Serial No. 173,831.

The present invention relates to lighting fixtures and is more particularly directed to the type of lighting fixture or lighting unit having a single centrally located electric lamp carried in a downwardly opening lamp socket.

One of the objects of the present invention is the provision of improved attaching devices for supporting the lamp socket from the loop customarily used in such lighting units.

10 Another object of the invention is to provide an improved frame for supporting the opaque deflector and diffusing disk of semi-indirect lighting units. These improvements relate more especially to a frame for this purpose which may be easily assembled when installing the fixture and which supports the deflector when the glass diffuser is removed, and to the means for releasably supporting the diffuser.

20 A further object of the invention is to provide improved means for supporting the structural parts of the lighting unit so that no strain is brought on the lamp socket.

25 Other and further objects of the invention will be apparent as the description proceeds.

The accompanying drawings show, for purposes of illustrating the invention, one of the many possible embodiments in which the 30 invention may take form, it being understood that the drawings are illustrative of the invention rather than limiting the same.

In these drawings:

Figure 1 is an elevational view with parts 35 in section showing a lighting fixture embodying the present invention;

Figure 2 is an enlarged view illustrating the upper part of the lighting unit;

Figure 3 is a fragmentary view of the socket 40 housing and locking ring employed in the upper part of the unit;

Figure 4 is a top plan view of the ring at the lower part of the unit for supporting the deflector and diffuser;

45 Figure 5 is a perspective view of one of the straps which supports the ring of Figure 4;

Figure 6 is a fragmentary view illustrating the assembly of the frame; and

Figure 7 is an elevational view illustrating 50 the removal of the lower glass diffuser.

As here shown, the lighting unit is of the pendant type and is carried at the lower end of a chain 10 by means of a suspension element such as a loop 11. As shown in Figures 1 and 2, this loop has a skirt 12 internally threaded as indicated at 13 and externally threaded as indicated at 14. A ring 17 is threaded into the threads 13 and this ring fixedly carries a disk 18 preferably fastened to it by upsetting the lower end of the ring onto the disk. The disk 18 has threaded holes 19 to receive attaching screws 20 for supporting a two-part porcelain lamp socket 21. The details of the lamp socket form no part of the present invention. To support other forms of lamp sockets or fixture parts, the ring 17 is internally threaded as indicated at 17.

An inverted cup-shaped sheet metal stamping 22 is provided with a hole to fit against the reduced lower end 15 of the loop so that the stamping 22 may be fastened onto the end of the loop by being interposed between the disk 18 and the loop 12. For convenience the upper end of this stamping 22 has holes punched in it to permit the screws 20 to pass through. The stamping 22 functions as a housing or cover for the socket and as a supporting element for other parts of the fixture to be described. An outer ornamental cover 23 is mounted on the loop as indicated and is held in the lower position by a nut 24 threaded onto the outside of the loop. When it is desired to raise the outer ornamental cover 23, the nut is released and the parts lifted up above the loop to give access to the lower part of the inner socket cover or housing.

The lower end of the socket cover or housing 22 is provided with vertical recesses 25 preferably three in number, and extend a short distance upwardly to holes 26 punched in the side of the socket cover or housing. A number of depending straps 27 are provided with inwardly bent upper ends 28. These inwardly bent ends are adapted to pass through the holes 26 in the socket cover and the upper portion of the straps 27 are adapted to lie in the recesses 25. To lock these straps in place, a locking collar 29 is provided. This collar is preferably held on

55

the socket cover by a rivet or pin 30 which passes through a Z-shaped slot 31 in the collar. When the collar is in the upper position as indicated in Figures 2 and 6, the straps may be inserted in place and when the 5 collar is lowered along the slot 31 and given a slight turn, it is impossible for the straps to become loosened from the socket cover or housing. In order to provide a convenient 10 grip for the collar 29 and that the outer ornamental socket cover may be held securely 15 in position, a flange 32 is provided at the upper end of the collar which engages the inner wall of the socket cover 23.

The straps 27 form the sole support for the 15 deflector 33 and glass diffuser 34 above referred to. The straps 27 are adapted to pass down along the neck 35 of a lamp bulb 36 and are then bent outwardly and twisted as indicated at 37. Below the twisted portion of 20 the straps, they extend vertically downward, as here indicated at 38, and the straps are then bent as indicated to form a horizontal portion 39, a vertical portion 40 and an outwardly directed foot 41. A ring 42 shown 25 more in detail in Figure 4 is provided with a number of outwardly directed lugs or projections 43 having holes 44 adjacent the outer wall 45 of the ring. The lower inner edge 30 46 of the deflector is outside of the straps 27 and rests on the lugs 43. Hooks 47 are pivotally mounted on the lower side lugs 43. These hooks may be made out of a piece of 35 twisted strap as indicated and held on a pin 48 passing through two ears 49 as indicated. These hooks are just the proper size and shape to engage the periphery 50 of the glass diffusing disk 34 and hold it in position.

In assembling the fixture, the socket is 40 wired in and mounted in the socket cover as previously described and the unit may be hung from the ceiling and connected with the house wires. The feet 41 of the straps 27 are passed through holes 44 in the ring 42 45 and these straps are then swung inwardly as indicated at the right of Figure 6 to bring the inwardly bent upper ends 28 into the slots or holes 26 in the socket cover. After this the collar 31 is moved down to lock the frame 50 together. The portions 39 and 40 of the straps securely embrace the ring 42. The socket cover, straps and ring form a substantial rigid self-supporting frame which will not collapse until it is disassembled. After 55 the frame has been assembled the deflector 33 may be tipped sidewise and passed upwardly over the ring in an obvious manner and then brought to rest on the lugs 43. The lamp 36 may be inserted in the socket and the diffusing disk caught in to two of the hooks 47 as indicated in Figure 7 and then the third hook snapped into position as shown in Figure 1. The fixture may be disassembled by reversing 60 the order of the above operations.

65 It will be noted that this frame can be as-

sembled and disassembled without the use of any tools whatever. It will also be noted that the present form of construction provides a rigid support for the deflector and makes it unnecessary to lower these deflectors 70 when making lamp renewals or for cleaning the fixture. The ability to support the deflector on a non-collapsing frame is particularly important in larger fixtures of this type which are sometimes provided with heavy 75 ornament such as a ring indicated at 33'.

It is obvious that the invention may be embodied in many forms and constructions within the scope of the claims, and I wish it to be understood that the particular form 80 shown is but one of the many forms. Various modifications and changes being possible, I do not otherwise limit myself in any way with respect thereto.

What is claimed is:

1. In a lighting fixture a downwardly opening lamp socket, a lamp bulb in the socket, a socket cover, a plurality of downwardly extending straps whose upper ends are inwardly bent to pass through holes in the socket cover, and a collar slidably mounted on the socket cover for limited longitudinal movement, the collar in one position overlying the upper part of the straps to lock them in place and in the other position being beyond the holes to permit insertion of the upper ends of the straps into the holes, the collar being angularly movable when in either extreme position to lock it against longitudinal movement.

2. In a lighting fixture a downwardly opening lamp socket, a lamp bulb in the socket, a socket cover, a plurality of downwardly extending straps whose upper ends are inwardly bent to pass through holes in the socket cover, a collar slidably mounted on the socket cover for limited longitudinal movement, the collar in one position overlying the upper part of the straps to lock them in place and in the other position being beyond the holes to permit insertion of the upper ends of the straps into the holes, the collar being angularly movable when in either extreme position to lock it against longitudinal movement, an outwardly and upwardly flaring opaque deflector for redistributing the light upwardly, and a ring of larger diameter than the bulb, the ring and deflector being supported by the lower ends of the straps.

3. In a lighting fixture a downwardly opening lamp socket, a lamp bulb in the socket, a socket cover, a plurality of downwardly extending straps whose upper ends are inwardly bent to pass through holes in the socket cover, a collar slidably mounted on the socket cover for limited longitudinal movement, the collar in one position overlying the upper part of the straps to lock them in place and in the other position being beyond the

- holes to permit insertion of the upper ends of the straps into the holes, the collar being angularly movable when in either extreme position to lock it against longitudinal movement, an outwardly and upwardly flaring 5 opaque deflector for redistributing the light upwardly, a ring of larger diameter than the bulb, the ring and deflector being supported by the lower ends of the straps, and a glass diffuser removably supported from the ring.
- 10 4. A semi-indirect lighting fixture comprising a single centrally located downwardly opening lamp socket, a support therefor, a socket cover, a lamp in the socket, a ring, a plurality of straps having hooks at their lower ends which pass through holes in the ring for supporting the ring and hooks at their upper ends which enter holes in the socket cover, a collar for locking the upper 15 ends of the straps in place, an outwardly and upwardly flaring deflector for redirecting light upwardly, and a glass diffuser under the ring for reflecting light onto the outside of the deflector, both the deflector and diffuser being removably supported from the ring.
- 20 5. A frame for semi-indirect lighting fixtures, comprising a horizontal ring substantially larger than a lamp bulb and having a plurality of vertical holes, a plurality of straps each insertible through one of the holes from above and having feet to extend underneath a portion of the ring to support it, and a socket cover to which the upper 25 ends of the straps are attached.
- 35 6. A frame for semi-indirect lighting fixtures, comprising a horizontal ring having outwardly extending projections, a plurality of straps each insertible through a hole in each projection and having feet extending underneath the projections to support the ring, the straps being inwardly bent to overlie the top of the ring and extending upwardly and inwardly, and a socket cover to which the upper ends of the straps are attached.
- 40 7. A frame for semi-indirect lighting fixtures, comprising a horizontal ring having outwardly extending projections, a plurality of straps each insertible through a hole in each projection and having feet extending underneath the projections to support the ring, the straps being inwardly bent to overlie the top of the ring and extending upwardly and inwardly, a socket cover having 45 holes to receive the upper ends of the straps, and a collar for locking the upper ends of the straps in the holes in the socket cover.
- 50 8. In a lighting fixture a socket cover having holes in the side walls, longitudinal depressions in the side walls extending from the holes to the lower edge of the socket cover, a plurality of straps lying in the depressions and having inwardly bent ends 55 entering the holes, and a collar slidably
- mounted on the socket cover and, when in its lower position covering the straps to lock them in place.
9. The combination with a support for a hanging lamp socket, an outwardly and upwardly flaring opaque deflector about the lamp for redirecting light upwardly, of a rigid self-supporting frame for supporting the deflector from underneath, said frame including a ring slightly smaller in diameter than the deflector and having outwardly extending deflector carrying lugs, a socket cover, and a plurality of straps hooked to the socket cover and the ring, the deflector when tilted slightly being removable sidewise to permit removing it from the frame. 70
10. The combination with a support for a hanging lamp socket, an outwardly and upwardly flaring opaque deflector about the lamp for redirecting light upwardly, of a rigid self-supporting frame for supporting the deflector from underneath, said frame including a ring slightly smaller in diameter than the deflector and having outwardly extending deflector carrying lugs, a socket 75 cover, a plurality of straps hooked to the socket cover and the ring, the deflector when tilted slightly being removable sidewise to permit removing it from the frame. 80
11. The combination with a support for a hanging lamp socket, an outwardly and upwardly flaring opaque deflector about the lamp for redirecting light upwardly, of a rigid self-supporting frame for supporting the deflector from underneath, said frame including a ring slightly smaller in diameter than the deflector and having outwardly extending deflector carrying lugs, a socket 85 cover, a plurality of straps hooked to the socket cover and the ring, the deflector when tilted slightly being removable sidewise to permit removing it from the frame, and a glass diffusing disk under the ring and supported from the ring in a position to reflect light onto the outside of the deflector. 90
12. The combination with a support for a hanging lamp socket, an outwardly and upwardly flaring opaque deflector about the lamp for redirecting light upwardly, of a rigid self-supporting frame for supporting the deflector from underneath, said frame including a ring slightly smaller in diameter than the deflector and having outwardly extending deflector carrying lugs, a socket 95 cover, and a plurality of straps hooked to the socket cover and ring, the deflector when tilted slightly being removable sidewise to permit removing it from the frame. 100
13. In a lighting fixture combination, a socket cover, a ring below the socket cover, the ring having a plurality of apertured outwardly directed lugs and a plurality of straps for supporting the ring from the socket cover, the straps being provided with 105
- 110
- 115
- 120
- 125

- an outwardly extending foot to pass through the apertures in the lugs and extend under the lugs and with an inwardly bent portion to overlie the top of the ring.
- 5 14. In a lighting unit, a loop having a wire passage and an internally threaded skirt, a nipple threaded into the skirt, a disk fixedly carried by the nipple, a lamp socket, and screws for fastening the lamp socket to the disk, the wires for connecting the socket passing through the passage and the nipple.
- 10 15. In a lighting unit, a loop having a wire passage and an internally threaded skirt, a nipple threaded into the skirt, a disk fixedly carried by the nipple, a lamp socket, screws for fastening the lamp socket to the disk, the wires for connecting the socket passing through the passage and the nipple, the lower end of the suspension element having an external shoulder, and an inverted cup-shaped socket cover having an aperture through which the lower end of the suspension element passes to bring the shoulder against the socket cover.
- 15 20 16. In a lighting unit, a loop having an internally threaded skirt, an inverted cup-shaped socket cover whose upper end is in engagement with the lower end of the skirt, a ring threaded into the skirt, a disk fixedly carried by the ring and extending underneath the top of the socket cover to hold it in place against the loop, a lamp socket in the socket cover, and screws for supporting it from the disk.
- 25 30 35 40 45 17. In a lighting fixture, a downwardly opening lamp socket, a lamp bulb in the socket, a socket cover, a collar mounted on the socket cover for limited longitudinal and angular movement, a plurality of downwardly extending straps whose upper ends are inwardly bent to pass through holes in the socket cover, the collar when in one position overlying the upper part of the straps to lock them in place, and an outer cover for concealing the socket cover, collar, and upper portions of the straps and preventing accidental movement of the collar to disengage the straps.
- 50 55 60 18. In a lighting fixture a suspension element, a downwardly opening lamp socket supported from the suspension element, a socket cover fixedly carried by the suspension element and surrounding the socket, a lamp in the socket, a collar slidably carried by the socket cover, and supporting straps hooked into the socket cover and having their upper ends inside the collar when it is in one position, said straps extending downwardly below the socket and secured to a ring spaced below the lamp.

Signed at Meriden, in the county of New Haven and State of Connecticut, this 7th day of March, 1927.

LEROY C. DOANE.
